UNITED STATES PATENT OFFICE

EDWARD AXELSON HELLSTRAND, OF GUILDFORD, ENGLAND

SLIDING WINDOW

Application filed March 3, 1928, Serial No. 258,797, and in Great Britain March 12, 1927.

This invention relates to vertically or horizontally sliding windows for use in connection with passenger transport and such as are used on vehicles, either single windows or two (or more than two) windows which slide alongside one another with a few inches of overlap to prevent the passage of draughts. Usually such windows slide horizontally, but in some cases vertically sliding windows of this kind are employed. The invention has for its object to simplify the movement and securing of the windows in any desired position, and provide other specified advantages.

15 In the accompanying drawings, illustrating various methods of carrying out the invention,

Figure 1 is a fragmentary elevation showing two windows at an overlapping position 20 and the device for locking them.

Figure 2 is a section on the line II-II of Figure 1,

Figures 3 and 4 are fragmentary views in plan and sectional elevation respectively, 25 showing an alternative locking device in position for slightly modified channels,

Figures 5 and 6, in section and elevation respectively, show alternative forms of channelling with a locking device as in 30 Figures 1 and 2, and

Figures 7 and 8, in section and plan respectively, show still further modified channels and also a modified form of the locking device as shown in Figures 3 and 4.

35 In the method illustrated by Figures 1 and 2, for two windows which slide over one another, the fixed or main channel 2 has sides 3 which for a certain distance from the base are parallel and thereafter converge as at 4 40 forming a section usually termed "undercut" (i. e., wider at the base than the mouth). Within this channel are slidably mounted two separate channels 5 and 6 attached respectively to the two windows 7 45 and 8, and they have vertical sides 9 which abut in the centre of the main channel, and also converging sides 10 which fit the sides 4 of the main channel. These sides 10 are formed initially to be somewhat higher than 50 the sides of the main channel, and thereafter

are folded as at 11 to engage the sides of the main channel.

The channels 5 and 6 are lined with resilient material 12, such as felt or rubber or cork, which does not harden nor perish, and this lining is so thickened at the base of each channel as to provide a substantially parallel sided groove for the reception of the windows 7 and 8. The bases 13 of these two channels are at a height above the base 14 of the main channel corresponding to the height of the latter's parallel sides 3. Into the space between these bases extends transversely of the channel a bar 15, whose underside is shaped to form two wedges 16, one under each of the channels 5 and 6. These wedges engage corresponding surfaces 17 on the base of the main channel, so that as the bar 15 is moved across the main channel its upper face is pressed against the bases of the two channels forcing them outwardly of the main channel, and, owing to the latter's inwardly converging sides, setting up a jamming action upon them which effectually prevents their accidental movement, or rattle, whilst the resilient lining 12 prevents any destructive effect on the window glass.

To operate the bar 15, one end 18 projects to the inner side of the vehicle and is screw-threaded to carry a clamping nut 19 which bears against the side of the main channel or against the face of the vehicle rail 20. Alternatively, operation of the wedge bar can be effected by a lever-operated cam or eccentric 21 (Figures 3 and 4), the advantage being that the lever can lie neatly against the main channel without projecting below it. If, therefore, the main channel is part of a frame hinged on its vertical edge it can be swung about its hinge outwardly of the vehicle side without obstruction.

In an alternative (Figures 5 and 6) in which the sliding edge of each window is protected by a strip 22 of extruded metal which at its lower edge is of T-section externally, the inner sides 23 of the main channel 24, also formed of extruded metal, are undercut to fit the strips 22. To provide, therefore, for the wedge member, a transverse cut 25 is made in the base of the chan-

nel and for the width of this cut the base of the channel is removed (see Figure 6). In this cut-away portion the wedge bar 15 is 5 slideable, and over it is a plate 26 which is secured to the main channel and has formed in it the co-acting wedge surfaces 17. Operation of the bar 15 applies a thrust to the strip 22 on the window causing it to be pressed against the upper portion of the main channel where the sides extend inwardly to form 10 the T-section.

As a further alternative, each channel 5 and 6 (Figures 1 and 2) may be fixed end-wise in the main channel and be sufficiently long to form the guide for a plain 15 plate glass or the like window (i. e. one devoid of framework). The glass is then adapted to slide between the felt or other lining 12, and, by making the sides of the 20 inner channel flexible, the wedge action set up by the sides of the main channel when the locking device is operated will cause the flexible sides of the inner channel to press upon the lining 12 and thus upon the glass 25 window thereby securely gripping it, but without risk of subjecting it to destructive stress. This action may be assisted by inclining the sides of the main channel less steeply than the adjacent sides of the glass- 30 engaging channel as illustrated in Figure 4.

A quick and neat method of operating the wedge bar is by a lever-operated eccentric, and this is illustrated in Figures 7 and 8. Here a wedge bar 15, constructed as in 35 the previous figures, is moved either inwardly or outwardly of the main channel by an eccentric reduced portion or offset pin 27 on the shaft 28 engaging a transversely elongated slot 29 in the bar 15 so that movement of an actuating lever 30 fast with the shaft 28 to the extreme positions (as indicated by the arrows) respectively, causes the slideable channels either to be gripped or freed. The sides of the main channel 2 40 and of the channels 5 and 6 in this construction do not converge towards the mouth as in Figures 1 and 2 but in effect form a modification of those in Figures 5 and 6, all the channels being made from sheet metal.

50 The main channel 2 has its vertical sides 31 parallel, and near the top these are bent inwardly and then upwardly to form a step 32 against which the slideable channels 5 and 6 of corresponding section and carrying the 55 windows 7 and 8 are pressed by the wedge bar. The space so left by the formation of the corresponding steps in the slideable channels is filled with resilient material 12 adapted to bear on the engaged edges of the 60 windows.

What I claim as my invention and desire to secure by Letters Patent of the United States is:—

65 1. In a sliding window for a vehicle, the combination of a main fixed channel hav-

ing undercut sides, a separately formed channel therein having sides which correspond with those of said main channel, and a device which is adjustable across the channels adapted to exert a thrust between their 70 bases whereby their respective sides are caused to grip one another, substantially as set forth.

2. Window channels according to claim 1, formed of strip metal bent to shape, the inner channel having its outwardly situated edges folded over to engage those of the main channel, and also having vertical inner sides which abut one another, substantially as set forth.

75 80 In testimony whereof I have signed my name to this specification.

EDWARD AXELSON HELLSTRAND.
